PACKAGING CONTAINER FOR CHEMICALLY IMPREGNATED WIPES OR THE LIKE

Ronald R. Gutkowski, Racine, Wis., assignor to
S. C. Johnson & Son, Inc., Racine, Wis.

Filed May 6, 1974, Ser. No. 466,924

Term of patent 14 years

Int Cl. D9—03

U.S. Cl. D9—222

FIG. 1

FIG. 2

FIG. 3

FIG. 4

FIG. 5

FIG. 6

FIG. 1 is a perspective view of a packaging container for chemically impregnated wipes or the like showing my new design;

FIG. 2 is a front elevational view;

FIG. 3 is a rear elevational view;

FIG. 4 is an elevational view looking from the right of FIG. 2;

FIG. 5 is a top plan view looking in the direction of the arrows 5—5 of FIG. 2; and

FIG. 6 is a bottom plan view looking in the direction of the arrows 6—6 of FIG. 2.

I claim:

The ornamental design for a packaging container for chemically impregnated wipes or the like, as shown.
